UNITED STATES PATENT OFFICE.

ROBERT GOSMAN, OF AMAGANSETT, NEW YORK.

PENCIL ATTACHMENT.

1,244,192.

Specification of Letters Patent. Patented Oct. 23, 1917.

Application filed February 8, 1917. Serial No. 147,322.

To all whom it may concern:

Be it known that I, ROBERT GOSMAN, a citizen of the United States, and a resident of Amagansett, in the county of Suffolk and 5 State of New York, have invented a new and Improved Pencil Attachment, of which the following is a full, clear, and exact description.

This invention relates to pencils or similar 10 articles of stationery and has particular reference to a means serving as a holder for a pen or pencil and constituting a receptacle for mucilage, paste, or the like.

Among the objects of the invention is to 15 provide a holder serving as a container for paste and having provision at one end for a pencil and at the other end for a combined rubber eraser, stopper and paste spreader or brush.

20 Another object of the invention is to provide a holder for both a pencil and a quantity of paste, the holder being provided with a slidable plug or follower between the paste and the pencil chamber, said follower being 25 adapted to be pushed by the unsharpened end of the pencil for the purpose of ejecting the paste from the opposite end of the holder.

With the foregoing and other objects in 30 view the invention consists in the arrangement and combination of parts hereinafter described and claimed, and while the invention is not restricted to the exact details of construction disclosed or suggested herein, 35 still for the purpose of illustrating a practical embodiment thereof reference is had to the accompanying drawings, in which like reference characters designate the same parts in the several views, and in which—

40 Figure 1 is a longitudinal sectional view of one form of my invention;

Fig. 2 is a plan view of the combined stopper, eraser and brush or spreader shown in Fig. 1;

45 Fig. 3 is a longitudinal section of my improvement slightly modified from Fig. 1;

Fig. 4 is a plan view of the combined cap, eraser and brush shown in Fig. 3; and

Fig. 5 is a modified form of brush or 50 spreader.

Referring now more particularly to the drawings, I show a holder 10 of tubular construction constituting a means for holding a pencil 11 or its equivalent, either for the 55 purpose of providing sufficient length for a short pencil or as a protector for the point

of the pencil when being carried in one's pocket. The holder, furthermore, constitutes a receptacle or chamber for a body or quantity of paste 12 or any other desired 60 commodity.

13 indicates a plug or follower fitted slidably within the holder and constituting in effect the bottom of the paste receptacle. Said follower is constructed preferably of 65 rubber or equivalent elastic material, whereby the likelihood of its becoming stuck in position due to the adhesiveness of the paste will be practically eliminated, as I have found in practice. If the follower 70 were made of rigid material, such as wood or the like, there would be some tendency for it to become fixed in position, especially if the device were not to be used frequently or extensively. While the plug or follower 75 is largely protected in its position within the holder from the evaporation of the paste, tending to cause the follower to become fixed, yet there is some tendency for this to take place, but while the follower is made of 80 flexible material, force applied thereto, as from the end of the pencil, serves directly and naturally to overcome such adhesive tendency. In other words, the follower is easily broken loose at any point at which it 85 may be stuck. Furthermore, another advantage of the use of an elastic follower is that it provides a more satisfactory protector or guard for the point of the pencil when the pencil point is housed within the holder. 90

With the holder and its follower arranged as indicated in the drawings, the chamber may be filled with paste of any suitable variety and by any desired or convenient means, such, for example, as a collapsible 95 tube projected into the open end of the holder remote from the follower. In fact under certain conditions, the injection of paste into the holder in this manner from a collapsible tube, will serve automatically 100 to force the follower toward the pencil end of the holder.

As a closure for the upper end of the holder, I provide a novel construction of stopper 14, the same embodying several different functions. Primarily this member constitutes a stopper portion 15 carrying a spreader 16 having a brush-like end 17 adapted to dip into the paste to bring forth a modicum thereof for application to any 110 desired work. The brush may be made as an integral part of the shank 16 of the stop-

per or, as indicated in Fig. 5, it may be composed of a bundle of bristles 17' held to the shank 16' by means of a thimble 18 made of metal or its equivalent. In any event the shank 16 or 16' is made preferably as an integral part of the stopper and the whole stopper device preferably is made of flexible rubber. The outer end of the stopper device constitutes a rubber pencil eraser 19 which serves its usual functions in connection with a lead pencil. It will thus be seen that the combination stopper for the upper end of the receptacle or holder serves at least three distinct yet correlated functions, and the same may be conveniently manipulated for its several functions without danger of smearing or soiling the operator's fingers. With the holder supplied, for example, with a quantity of library paste or thick mucilage, the operator may remove the stopper by grasping the eraser portion 19 thereof and while so removing it a modicum of the paste will be withdrawn along with the brush 17, and hence 25 may be transferred thereby and spread upon any desired surface. When the stopper is returned to its normal position, it constitutes an effective airtight closure for the holder, preventing the smearing, spreading or evaporation of the liquid or semi-liquid contents. The shank 16 or 16' being made of flexible rubber facilitates the spreading action above described.

As shown in Figs. 3, 4 and 5, the closure member includes a thimble 20 having the outer end fitted permanently upon the stopper and adapted to fit over the outer end of the holder. The sleeve provides a little more security for the operator's fingers in manipulating the device and also reduces any tendency for the paste to become smeared or spread upon the outside of any of the parts.

In the practice of this invention, when the brush will no longer reach the contents of the holder, the operator has but to push upwardly or inwardly upon the pencil, causing the follower to glide along the inner surface of the holder and push the mass

of paste upwardly toward the opposite open end of the holder, so as to be in position to be reached with the brush. This operation may be repeated when necessary so long as there is any paste left in the holder. The device is simple and cheap of construction and convenient and reliable in practical operation. I am aware that numerous attempts have been made to produce a practical combination pencil and mucilage or paste container and hence I do not claim the same broadly.

I claim:

1. The combination of a tubular holder of uniform cross section adapted to receive a pencil point at one end, a resilient follower slidably fitted within the holder against which the end of the pencil is adapted to impinge, said follower being movable along the holder by force applied to the pencil, the opposite end portion of the holder together with the follower constituting a receptacle for paste, and a combined pencil eraser, stopper and paste spreader carried by the opposite end of the holder.

2. In a pencil attachment of the character set forth, the combination with a tubular holder adapted to contain a quantity of paste, of a combined integral pencil eraser, resilient stopper, and paste spreader serving to seal said paste receptacle, and a thimble fitted upon the stopper and slidable upon the outer end of the holder while the stopper is projected into the end of the holder.

3. The herein described article of stationery comprising a rigid tubular holder adapted to hold a pencil at one end and paste at the other end, a member fitted within the holder between the paste and the pencil portions thereof and adapted to be moved along the holder by application of the pencil to deliver the paste to the opposite end of the holder, and an integral eraser stopper and brush carried by the open end of the paste end of the holder.

ROBERT GOSMAN.
